CLAIM

We claim the ornamental design for a core for a pillow, as shown and described.

DESCRIPTION

1. Core for a pillow

1.1 : Top perspective

1.2 : Front

1.3 : Back

1.4 : Top

1.5 : Bottom

1.6 : Left

1.7 : Right

1.8: Enlarged longitudinal cross sectional view taken along line **1.8-1.8** in **1.2**

1.9: Enlarged longitudinal cross sectional view taken along line **1.9-1.9** in **1.2**

1.10 : Lateral cross sectional view taken along line **1.10-1.10** of **1.7**

1.11: Lateral cross sectional view taken along line **1.11-1.11** in **1.7**

1.12: Perspective view shown in an environment of use
The broken line portion of the figure drawings is included to show portions of the article and environment that form no
